UNITED STATES PATENT OFFICE

SAM I. ESSES AND EDWARD I. ESSES, OF NEW YORK, N. Y.

SERVICE STATION

Application filed March 12, 1929. Serial No. 346,289.

This invention relates to service stations. It is particularly directed to coin controlled apparatus for dispensing gasoline, oil and water for automobiles and the like motor conveyances.

An object of this invention is to provide in a service station of the character described, dispensing means operable only upon receiving coins of the proper denomination.

10 A further object of this invention is to provide apparatus of the character described having improved means for indicating the quantity of liquid dispensed, and for preventing use of the device when the supply of said liquid is exhausted.

Another object of this invention is to provide apparatus of the character described having means for vending different quantities of liquid for different amounts of money.

20 A still further object of this invention is to provide in a device of the character described, means for preventing the purchaser from pumping more than a predetermined amount of liquid.

25 A still further object of this invention is to provide a service station of the character described having means controlled by a coin of proper denomination for permitting use of an unlimited amount of water.

30 Still another object of this invention is to provide apparatus of the character described having means for automatically replacing the oil container, gas and water hose to their normal positions within the casing after use.

35 Another object of this invention is to provide a neat, compact and rugged assembly and apparatus of the character described, of economical construction, which shall comprise few and simple parts, which shall be easy to operate, and withal practical and efficient to a high degree in use.

40 Other objects of this invention will in part be obvious and in part hereinafter pointed out.

45 The invention accordingly consists in the features of construction, combinations of elements, and arrangement of parts which will be exemplified in the construction hereinafter described, and of which the scope of

application will be indicated in the following claims.

In the accompanying drawings, in which is shown one of the various possible illustrative embodiments of this invention,

55

Fig. 1 is a front elevational view of a service station embodying the invention with parts broken away to show the interior construction;

Fig. 2 is a side elevational view of the apparatus shown in Fig. 1;

Fig. 3 is an enlarged detailed elevational view of the gasoline pump controlling mechanism;

Fig. 4 is a cross-sectional view taken on line 4—4 of Fig. 3;

Fig. 5 is a cross-sectional view taken on line 5—5 of Fig. 3;

Fig. 6 is an enlarged detailed view in elevation of the oil dispensing mechanism;

Fig. 7 is a cross-sectional view taken on line 7—7 of Fig. 6;

Fig. 8 is an elevational view of the water dispensing mechanism;

Fig. 9 is a top elevational view of the water hose retrieving means.

Referring in detail to the drawings, 10 designates a service station in the form of apparatus for vending oil, gas and water to motorists, and for like purposes. Said station comprises a metal casing 11 secured to the grooved or other suitable base 12, at its lower edge portion 13. Said casing comprises a front wall 14, side walls 15, 16 and a top wall 17. The latter wall may be rounded or otherwise suitably shaped for ornamental purposes. Mounted on said top wall 17 is lamp 18 of any suitable attractive construction for illuminating or advertising purpose. At the lower rear portion thereof, 80 said casing is formed with an extension 19 having an opening 20. A door 21 hinged at its upper edge 22 may be locked to said casing as by lock 23 shown in Fig. 2.

90 In the front face 14 of said casing are a number of slots for receiving coins for controlling the operation of the dispensing devices. The kind of liquid dispensed and the character of the coins to be inserted are indicated by suitable markings adjacent the 100

respective slots. Thus at the left of said front wall, a slot 25 may be marked "Oil" and "1 Quarter". Secured to said front wall 14 below said slot, and extending rearwardly 5 from said wall is an elongated horizontal sleeve 26 of rectangular cross-section. A coin guide member 27 communicating with slot 25 leads down to said sleeve 26 which is provided with a slot 28 for permitting the coin 10 deposited in said slot 25 to drop into said sleeve.

Mounted within said sleeve 26 is a rack 29 having gear teeth 30 formed at the lower edge thereof. An elongated plate 31 is slidably mounted within said sleeve 26 in parallel relation to said rack 29. Integrally formed with said plate 31 is an elongated stem or rod 32 extending within said sleeve and thru a slot 33 formed in the front wall 20 14 of the casing. Said rod 32 terminates in a handle member 34 for reciprocating said plate 31 within said sleeve 26. An upstanding arm portion 35 integrally formed with said plate 31 at one end thereof, is adapted 25 to ride in slot 36 formed in the upper wall 37 of sleeve 26 and serves to limit the movement of said plate 31 in both directions. A projection 38 fixed to the inner face of said plate 31 extends between said plate and rack 30 29. A pair of spaced projections 39 integrally formed with said rack 29 extend inwardly from the inner face thereof, substantially in alignment with said projection 38. Extending beneath said plate 31 which is of 35 less height than the sleeve 26, is a wall 40 slidably supporting the plate 31. It will now be understood that a coin 41 inserted thru slot 25 and passing downwardly thru guide 27 and slot 28 will drop on said wall 40 and between the projections 38 and 39. Should this occur, a pulling force on the handle 34 will cause sliding movement of both plate 31 and rack 29 since these members are interlocked by the coin 41 abutting the 45 projections 38 and 39. Should the coin 41 be smaller than the space between the upper and lower projections 39, the projection 38 will merely push said coin thru said space and the rack 29 will hence not be moved 50 by pulling the handle 34. Extending beneath said sleeve member 26 is a coin guide 42 interconnecting with an opening 43 in said bottom wall 40 for receiving the coins 41 when the plate 31 and interlocked rack 29 have been moved a sufficient distance to 55 the left as shown in Fig. 6. The coin thus runs down said chute 42 and into the coin deposit box 44.

Means is provided for pumping a predetermined quantity of oil when a proper coin has been inserted in slot 25 and the rack bar moved as described above. To this end, a gear 45 is rotatably mounted on shaft 46, a one-way roller clutch 47 being interposed 60 between said gear and said shaft. Fixed to

said shaft 46 is a plate 48 adapted to be rotated only when the rack 29 is being moved forward toward wall 14. Return movement of the rack will only rotate gear 45 without affecting either shaft 46 or the plate 48. Said return movement of the rack 29 is effected by a coil tension spring 49 fixed on its bottom end 50 in any suitable manner within the casing and connected to the rear end 51 of plate 31 as by a belt 52 rolling over a pulley 53. A pin and slot connection 54 between the plate 31 and rack bar 29 is adapted to return said rack bar to the position shown in Fig. 6 when said plate is moved to the right under the influence of tension spring 49. The relative sizes of the gear 45 and rack 29 is such that a single forward stroke of the plate 31 will cause complete revolution of said plate 48. Mounted on a bottom supporting plate 55 fixed within the casing 11 adjacent edge portion 13 is a cylinder 56, disposed directly beneath said plate 48. Within said cylinder is a piston 61 having a piston rod 62 extending thru a suitable opening 63 in the top wall 64 of said cylinder. A connecting rod 65 pivotally connects said piston rod 62 and an eccentric pin fixed to plate 48 as at 66 and 67 respectively. Mounted within the casing 11 as on plate 55 is an oil barrel 68 supported within said casing 11 in a slightly inclined position as shown in Fig. 1 of the drawings. Interconnecting the barrel 68 and the bottom of the cylinder 56 is a short pipe 69 having a one-way check valve 70 interposed therein for a purpose hereinafter appearing.

The front wall 14 of casing 11 is provided with an opening 71. Mounted on the inner surface of said front wall adjacent the lower edge of said opening is a trough member 72 having a bottom wall 73. Flow-off or drip pipe 74 interconnects the bottom of said trough with the top portion of the barrel 68. Mounted on said bottom wall 73 is a container 75 adapted to be inserted thru the opening 71 of front wall 14. A handle member 76 may be provided for manipulating said container 75.

A retrieving mechanism 77 is provided for drawing said container 75 back into its position as shown in Fig. 6 when said container 115 has been withdrawn from said opening and released after use. Said retrieving mechanism 77 comprises a drum 77a rotatably mounted on a shaft 78, said shaft and drum being interconnected by a spiral spring 79. A chain 80 is adapted to wind on the outer surface of said drum and interconnects the latter with the container 75. A pipe 81 connected to the bottom of the cylinder 56 extends upwardly and terminates in a downwardly curved portion 81a disposed directly above the container 75. A one-way check valve 82 is interposed in said pipe 81 adjacent said cylinder 56.

The operation of the device will now be 120

clear. The purchaser need merely insert a coin in slot 25 for interlocking plate 31 and rack member 29. If the coin is too large, it will not enter the slot 25. If it is too small 5 it will not interlock with said members 29 and 31. If the coin is of the proper denomination, said members will be interlocked and the plate 48 given a complete revolution. This 10 movement of plate 48 will cause the piston 61 to reciprocate vertically in the cylinder 56. On the upstroke of the piston, oil will be drawn in from the barrel 68 thru pipe 69 and check valve 70 and, on the down stroke, the oil will be forced out thru check valve 82, 15 pipe 81 and into container 75. The purchaser may then pull out the container and pour the oil into the tank in the automobile. A glass window 83 may be provided on the front wall 84 of the container for permitting 20 observation of the oil level within said container. The mark 84a adjacent said window 83 indicates the proper level of the oil for a full measure.

A register 85 for indicating the number of 25 measures of oil vended may be provided. Said register is preferably mounted on the front wall 14 directly above the sleeve 26, and may be provided with a pivoted arm 86, the end portion 87 of said arm extending in 30 the path of an upstanding projecting 87a formed with rack 29. Upon movement of said rack for pumping oil, the arm 86 will thereby be moved for actuating the register. A spring 88 is adapted to return the arm 86 35 to its original position upon return of the rack 29 to the normal position. Said register may be further provided with a disc 89 adapted to rotate progressively as the arm 86 is actuated. Said disc 89 is formed with 40 peripheral notch 90. Pivotaly mounted on a fixed shaft 91 is a bell crank 92 having an arm 93 maintained in contact with the periphery of disc 89 as by a light spring 94. The upper portion 95 of said bell crank is 45 adapted to support a plate 96 which slidably extends within the sleeve 97 fixed to the front face of wall 14 above slot 25. When the disc 89 has been rotated a complete revolution, by a predetermined number of oscillations of 50 arm 86, the end portion 93 of the bell crank 92 will enter the notch 90 under the influence of spring 94. This movement will disengage the upper end 95 of said bell crank from the plate which is thereby permitted to drop behind the slot 25 for obstructing the same. 55 Further deposit of coins will not thereafter be possible until proper readjustment of the parts. The register 85 may be so adjusted that the plate 96 is caused to obstruct the slot 25 when the oil barrel 68 is substantially empty.

The service station 10 is further provided with means for dispensing gasoline. To said end, a gasoline tank 100 is preferably em- 60 bedded in the ground beneath the casing 11

in the usual manner. Said tank is connected to an ordinary gasoline hand pump 101 by a pipe 102. A crank handle 103 extending beyond said casing is fixed to a shaft 104 rotatably mounted within the casing and extending thru said wall 16 thereof. Fixed on said shaft 104 are spaced gears 105 and 106 which mesh with a pair of vertical racks 105a and 106a interconnected by a cross bar 107. Said racks extend into the pump 101 70 and are adapted when moved upwardly by rotation of handle 103 in the proper direction to pump gasoline thru the pipe 108 and a hose 109 mounted in a manner hereinafter described. 75

A coin control mechanism is provided for permitting the purchaser to pump predetermined quantities of gasoline. For this purpose the front wall 14 in the casing is provided with two coin slots 110, 111. One of 80 said slots 110 may be marked Half dollar and the other slot 111 may be marked 2 Dimes. Extending inwardly from said wall 14 below said slots 110, 111 are horizontal sleeve members 110a and 111a respectively. Coin 85 chutes 110b, and 111b provide passages for coins from said slots to the interior of sleeves 110a, and 111a respectively. Slidably mounted within said sleeves 110a, 111a are plates 112, 113, respectively. Said plates 112, 90 113 are provided with stems 112a, and 113a respectively, extending thru openings 112b and 113b in a front wall 14 and terminating in heads 112c, 113c. Said plates 112, and 113 are formed with vertical slots 114, 115 95 respectively on the inner faces thereof. Slot 114 is adapted to receive the half dollar deposited into slot 110. Should a coin of a smaller denomination be inserted in slot 110, 100 said coin being thinner than the half dollar 105 will drop thru a slot 116 formed in the bottom wall 117 in sleeve 110a. Slot 115 in plate 113 is adapted to receive the dimes inserted thru slot 111. The height of the plate 113 is equal to the height of the two dimes as 110 clearly shown in Fig. 3. Tension springs 116a secured to the rear end portions 112d, 113d of said plates 112 and 113 are adapted to normally retain said plates in retracted 115 position as shown in Figs. 3 and 5. Rotatably mounted on a shaft 117a journaled in bearing brackets 118 fixed to wall 14 are a pair of substantially symmetrical levers 119, 120. Lever 119 is provided with an arm 119a having an off-set portion 119b and an extension 119c projecting into the lower portion of slot 114. Likewise, lever 120 is provided with an arm 120a having an off-set portion 120b and an extension 120c projecting into the upper portion of slot 115. It will now be 120 understood that upon insertion of the proper coin into chute 110b, the coin dropping into slot 114 will be interposed between the end portion 112d and plate 112, said extension 119c of the lever 119. When the half dollar 125

therefore, is in said slot 114, the purchaser may pull the head 112c for causing pivotal movement of lever 119 about the shaft 117a for a purpose hereinafter appearing. Said end portion 112d and the projection 119a are formed with inwardly extending projections 121 normally spaced apart a distance slightly less than the diameter of a half dollar piece. Thus, should a smaller coin be inserted in slot 110, the coin would not be retained within said slot 114 by said projections 121, but would fall thru slot 116. Likewise, when the two dimes are inserted in slot 111 and said dimes are lodged within slot 115, one above the other, the upper one of said dimes is interposed between the extension 120c of lever 120 and the end portion 113d of plate 113. A pulling force on head 113c will hence cause pivotal movement of the lever 120. The lower dime may be supported by a pair of spaced projections 122 formed at the inner surface of said plate 113. Obviously, if only one dime is inserted into the slot 111, said dime would be ineffective to interlock the plate 113 and the lever 120. Upon outward movement of either of plates 112, 113 the coins are brought into alignment with the coin chutes 124 and 125 respectively whence the coins are conveyed to the coin deposit box 44.

Means are provided for preventing operation of the pump 101 until the proper coins have been deposited in slots 110, and 111, and for preventing the purchaser from pumping more than a predetermined quantity of gasoline, corresponding to the coins deposited. Attached to lever 119 adjacent the off-set portion 119b thereof, is a depending integral arm 126 extending below said sleeve members 110a, 111a. Pivottally attached to said arm 126 at its lower end portion 127 as by a pin and slot connection 128, is a horizontal slidably mounted member 129. The latter comprises a bar 130 mounted on a pair of fixed aligned guides 131 disposed on either side of the shaft 104. Formed with said bar 130 are a pair of symmetrically spaced horizontal U-shaped members 131, 132, and slidably mounted within member 131 is a plunger 133 having a pin and slot connection 134 with said member. A coil compression spring 135 interposed between the rear end of said plunger and wall 136 of said member 131 normally maintains said plunger in extended position, as shown in Fig. 3. Attached to the cross bar 107 which interconnects the racks 105a, 106a is a vertical depending member 137 disposed in alignment with said U-shaped members 131 and provided with one-way ratchet teeth 138 adapted to engage a tooth portion 139 formed at one end of plunger 133.

Thus when the parts are in the position illustrated in Fig. 3, turning movement of the handle 103 for pumping gasoline is prevented since the racks 105a, 106a connected to the

pump mechanism within pump 101, cannot move upwardly due to the locking interengagement of teeth 138, 139. However, when the lever 119 is rotated in clockwise direction as seen in Fig. 3, the bar 130 is translated to the left for releasing member 137. Said member 137 is further provided with one-way ratchet teeth 140 disposed in a direction opposite to teeth 138. A plunger 141 slidably mounted in U-shaped member 132 in a manner similar to the mounting for plunger 133 is provided with a tooth 142 and adapted to interlock with said teeth 140 of member 137 upon movement of the bar 139 to the left. Such movement of course, takes place when the lever 119a is rotated in clockwise direction to permit actuation of the pump for dispensing the gasoline. Thus, actuation of the pump handle in a direction for moving the racks 105a, 106a downwardly is prevented while the bar 130 is moved to the left. As will hereinafter be pointed out, said bar 130 will be automatically moved to the right only when the full and proper amount of liquid has been pumped.

Attached to the upper ends of levers 119, 120 as by a pin and slot connection 150, 151 are a pair of stop members 152, 153 for limiting the upward movement of ratchet member 137 and consequently the actuation of the pump 101 for dispensing the gasoline. Said stop member 152 comprises a horizontal arm 154, an upstanding vertical arm 155 extending from one end of said arm 154, and a horizontal arm 156 extending from the upper end of said arm 155. Said arm 154 is slidably received in the guide member 157, whereas the arm 156 is slidably received in a guide member 158. Actuation of the lever 119 will thus cause reciprocation of said member 152. The stop member 153 comprises a horizontal arm 159, a depending vertical arm 160 and a horizontal arm 161 extending from the lower end of said arm 160. Arm 159 of said member 153 is likewise slidably received in the guide member 157, whereas the arm 161 is slidably received in a guide member 162 similar to and spaced directly below said guide member 158. Said arm 154 of member 152 is provided with a slot 163 wherein is received at the right end thereof as shown in Fig. 3, a pin 164 fixed to the inner surface of arm 159. It will now be understood that rotation of lever 119 will move member 152 to the right without moving member 153. However, upon rotating the lever 120, both members 153 and 152 will be moved to the right since pin 164 which is fixed to arm 159 contacts a portion of arm 154 at the end of slot 163. Thus, lever 119 is rotated in a counter-clockwise direction upon actuation of either plate 112 or 113.

The arm 156 is provided with a ramped portion 165 and a projection 166. Mounted within the housing 167 formed with guide

115

120

125

130

member 158 is a ball 168 normally pressed against upper surface of said arm 156, by spring 169. Formed in the upper surface of said arm 156 is a notch 170 adapted to receive the lower portion of said bell 168 upon movement of said member 152 to the right, for retaining said member against accidental movement. A tension spring 171 fixed at one end 172 thereof, attached to said member 152 at its opposite end, normally tends to move said member 152 to the left. Arm 161 is likewise provided with a ramped portion 165a and notch 170a for receiving a spring pressed ball 168a.

Upon insertion of a half dollar in slot 110, the coin drops thru chute 110b into slot 114, thus interlocking the extension 119c of lever 119 with plate 112. The plate may then be pulled outwardly for rotating lever 119 in a clockwise direction. Such rotation will release plunger 133 from engagement with the ratchet member 137 and will simultaneously move member 152 to the right, bringing the ramped portion 165 and extension 166 directly above cross member 107. This movement will also cause the spring pressed plunger 141 to abut teeth 140 of said ratchet member. The pump handle 133 may then be rotated for pumping liquid but not in a reverse direction. During such pumping action, the gears 105, 106 meshing with rack 105a, 106a, will move the cross member 107 upwardly. This movement, which is now permitted since the plunger 133 is retracted, may then continue until said cross member 107 strikes the ramped portion 165 of member 152. Upon contact with said ramped portion 165, the member 152 will be caused to slide slightly and to the left causing the ball 168 to be lifted from the notch 170 and thus permitting the spring 171 to move the member 152 to the left, and thereby rotating lever 119 in a counterclockwise direction to again bring plunger 133 into contact with ratchet 137. Further pumping is thereafter prevented, and the pump handle must be rotated in the opposite direction to again lower the ratchet member 137 before any pumping action may again take place. Upon insertion of 2 dimes in slot 111, the same action takes place except that both levers 119 and 120 are rotated simultaneously (due to the pin and slot connection 163, 164). Thus the lower arm 161 is brought into alignment 55 above with the bar 107 and only the lesser quantity of liquid can then be pumped. When the bar 107 strikes the ramped portion 165a of the arm 161, a similar unseating action of the spring pressed ball 167a takes place to permit return movement of member 153 under the influence of tension spring 171a. At the end, such return movement of member 153, the pin 164 moving in the slot 163 in arm 154 strikes said arm for unseating ball 168 to permit retraction of mem-

ber 152 by spring 171. It will be noted that the purchaser will not be able to rotate the handle 103 for lowering the bar 107 until said bar strikes either arm 161 or 156.

The hose 109 for receiving gasoline is wound on a drum 175 provided with a retrieving spring 176. Thus, before starting the pumping operation, the hose is withdrawn by pulling the nozzle 177 and inserting the tip of said nozzle within the proper gas tank opening. Said nozzle is provided with a small bell crank 178 which is movable by pin 179 connected thereto for causing the hook end 178a of said bell crank to engage the undersurface of the gas tank adjacent the mouth while the gas is being pumped. The nozzle is thus rigidly supported in the mouth of the gas tank while the purchaser is operating the handle 103. After the full quantity of liquid has been pumped, pin 179 may be pushed downwardly for releasing the bell crank 178. Upon being released, the nozzle may then be drawn back to the casing since spring 176 will then wind the hose 109 on the drum 175.

Coin control means is provided for vending water. To this end, the front wall 14 of the casing 11 is provided with a slot 180 marked Water. Below said slot may be designated the coin to be inserted as for instance 1 Nickel. Secured to said wall 14 is a coin chute 181 for guiding the coin deposited in said slot. A bell crank 182 pivotally mounted beneath the outlet opening 183 of said chute is provided with an arm 184 adapted to receive the coin 185 as shown in Fig. 8. Said bell crank is provided with a second arm 186 adapted to contact the rear portion of said coin. Attached to said front wall 14 is a tubular member 187 having an opening 188 in the end wall 193 thereof. Slidably mounted within said tubular member and extending thru said opening 188 and an opening 190 in said front wall, is a plunger 189 having a fixed collar 191 extending within said tubular member 187. A coil compression spring 192 interposed between said collar 191 and said end wall 193 normally presses said collar against the rear surface of said front wall 14. Said plunger is further provided with a portion 194 extending beyond said wall 14 and having a head 195. It will now be obvious that upon pushing the plunger 189 inwardly against the pressure of the spring 192, the force is transmitted thru the coin 185, thus causing clockwise rotation of the bell crank 182. The coin thereafter drops into any suitable receptacle. If no coin has been inserted in the slot 180, the inward movement of the plunger will not affect the bell crank. Mounted within the casing 11 as on a support 196 is a horizontal shaft 197 rotatably supporting a drum 198. Said drum is provided with a peripheral helical groove 199 for winding the

water hose 200. The inner end 201 of said hose is connected to a valve 202, which may be connected thru a pipe 203 to any suitable water supply under pressure. Pivottally attached to said valve 202 is an actuating member 204, the mechanism being such that rotation of said member 204 in a counterclockwise direction will open the valve to permit flow of water from the hose. A spiral spring 205 normally maintains the hose in wound condition on the drum, the nozzle 206 of said hose being normally drawn against the front wall 14 of the casing. Arm 184 of the bell crank 182 is provided with a detent 207 adapted to engage within the groove 208 formed in a tubular portion 209 adjacent the nozzle of the hose. Thus the hose cannot be drawn out while the detent 207 extends within the groove 208. However, upon the insertion of a proper coin in slot 180, rotation of the bell crank 182 may be effected for lifting the detent and for permitting withdrawal of the hose.

Means is provided for automatically pivoting the actuating member 204 from the normally valve closing position shown in Fig. 8 upon drawing the hose out to start the flow of water. To this end, an end wall 210 of the drum 198 is provided with a spiral groove 211. A pin 212 fixed to a block 213 slidably mounted on the actuating member 204 extends into said groove 211. Upon drawing the hose from the casing, the drum 198 rotates and the pin 212 moves inwardly towards the center of the drum because of the spiral groove 211. When said pin 212 contacts the portion of the wall 210 on the inner end of the spiral groove, as designated by numeral 214, further outward movement of the hose will rotate said actuating arm 204 for opening the valve 202. The nozzle 206 obviously may be inserted in the automobile radiator opening. After use of the water, release of the hose will permit the retrieving spring 205 to rewind the hose and close the water valve and bring the parts to their original position.

Although the oil and gasoline pumps shown herein are hand operated, it is understood that electric motors or the like means may be provided for actuating said pumps.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described our invention, we

claim as new and desire to secure by Letters Patent:

1. In apparatus of the character described, a liquid pump, an elongated member associated with said pump adapted to be lifted upon operating the pump for dispensing liquid therefrom, said member being formed with two sets of ratchet teeth, the teeth of one set being disposed oppositely to the teeth of the other set, a slidably mounted member having a pair of spring pressed pawls mounted thereon and slidably connected thereto by pin and slot connections, each of said pawls being adapted to coact with one of said sets of teeth respectively. 70

2. In apparatus of the character described, a liquid pump, an elongated member associated with said pump adapted to be lifted upon operating the pump for dispensing liquid therefrom, said member being formed with two sets of ratchet teeth, the teeth of one set being disposed oppositely to the teeth of the other set, a slidably mounted member having a pair of spring pressed pawls mounted thereon, and slidably connected thereto by pin and slot connections, each of said pawls being adapted to coact with one of said sets of teeth respectively, and means for slidably moving said slidably mounted member for releasing one of said pawls from engagement with one set of teeth and simultaneously moving the other pawl into engagement with the other set of teeth. 85

3. In apparatus of the character described, a liquid pump, an elongated member associated with said pump adapted to be lifted upon operating the pump for dispensing liquid therefrom, said member being formed with two sets of ratchet teeth, the teeth of one set being disposed oppositely to the teeth of the other set, a slidably mounted member having a pair of spring pressed pawls mounted thereon, and slidably connected thereto by pin and slot connections, each of said pawls being adapted to coact with one of said sets of teeth respectively, and means for slidably moving said slidably mounted member for releasing one of said pawls from engagement with one set of teeth and simultaneously moving the other pawl into engagement with the other set of teeth. 100

4. In apparatus of the character described, a liquid pump, an elongated member associated with said pump adapted to be lifted upon operating the pump for dispensing liquid therefrom, said member being formed with two sets of ratchet teeth, the teeth of one set being disposed oppositely to the teeth of the other set, a slidably mounted member having a pair of spring pressed pawls mounted thereon, and slidably connected 105

- thereto by pin and slot connections, each of said pawls being adapted to coact with each one of said sets of teeth respectively, and means for slidably moving said slidably mounted member for releasing one of said pawls from engagement with one set of teeth and simultaneously moving the other pawl into engagement with the other set of teeth, said means comprising a lever pivoted 5 immediately the ends thereof, and operatively connected adjacent one end thereof to said slidably mounted member, coin controlled means for pivotally moving said lever, and means operatively connected adjacent the other end of said lever adapted to be moved into the path of said first member upon pivotally moving said lever, for limiting the pumping operation.
5. In apparatus of the character described, a liquid pump, an elongated member associated with said pump adapted to be lifted upon operating the pump for dispensing liquid therefrom, said member being formed with two sets of ratchet teeth, the 10 teeth of one set being disposed oppositely to the teeth of the other set, a slidably mounted member having a pair of spring pressed pawls mounted thereon, and slidably connected thereto by pin and slot connections, each of said pawls being adapted to coact with one of said sets of teeth respectively, means for slidably moving said slidably mounted member for releasing one of said pawls from engagement with one set of teeth and simultaneously moving the other pawl into engagement with the other set of teeth, said means comprising a lever operatively associated with said slidably mounted member and coin controlled means for pivotally moving said lever, a second lever pivoted mediate- 15 ly the ends thereof, coin controlled means for pivotally moving said second lever, means associated with one end of said second lever adapted to be moved into the path of said first member for limiting the pumping operation, and means associated with said second lever for moving said first lever therewith, said means being arranged for permitting movement of said first lever without moving said second lever.
6. In apparatus of the character described, a liquid pump, an elongated member associated with said pump adapted to be lifted upon operating the pump for dispensing liquid therefrom, said member being formed with two sets of ratchet teeth, the teeth of one set being disposed oppositely to the teeth of the other set, a slidably mounted member having a pair of spring pressed pawls 20 mounted thereon and slidably connected thereto by pin and slot connections, each of said pawls being adapted to coact with one of said sets of teeth respectively, means for slidably moving said slidably mounted member for releasing one of said pawls from engagement with one set of teeth and moving the other pawl into engagement with the other set of teeth, said means comprising a lever pivoted mediate- 25 ly the ends thereof, coin controlled means for pivotally moving said lever, and means operatively connected adjacent the other end of said lever adapted to be moved into the path of said first member, for limiting the pumping operation, a second lever pivoted mediate- 30 ly the ends thereof, coin controlled means for pivotally moving said second lever, means associated with one end of said second lever adapted to be moved into the path of said first member for limiting the pumping operation, and means associated with said second lever for moving said first lever therewith, said means being arranged for permitting movement of said first lever without moving said second lever.
7. In a service station of the character described, mechanism for dispensing liquid including a liquid pump, a member adapted to be moved upon actuation of said pump, and stop means for preventing actuation of said mechanism after a predetermined quantity of liquid has been dispensed, said means comprising a pivoted lever, coin controlled means for pivotally moving said lever and a member associated with said lever adapted to be moved into the path of said movable member upon actuation of said lever.
8. In a dispensing apparatus of the character described, in combination, a liquid pump, a member adapted to be moved upon actuation of said pump, and means controlled by coins of various denominations for permitting operation of the pump for dispensing correspondingly varying predetermined quantities of liquid, said means including a pair of pivoted levers, means for pivotally moving said levers, a member associated with each lever having a portion adapted to be moved into the path of said movable member upon actuation of said levers, said portions being spaced from one another.
9. In a dispensing apparatus of the character described, in combination, a liquid pump, a member adapted to be moved upon actuation of said pump, and means controlled by coins of various denominations for permitting operation of the pump for dispensing correspondingly varying predetermined quantities of liquid, said means including a pair of pivoted levers, means for pivotally moving said levers, a member associated with each lever having a portion adapted to be moved into the path of said movable member upon actuation of said levers, said last named portions being spaced from one another, said last named members being interconnected by a pin and slot connection whereby upon actuation of one of said levers, one only of said

last named portions will be moved into the path of the movable member and upon actuation of said other lever, both of said portions will be moved into the path of said movable member.

10. In a dispensing apparatus of the character described, in combination, a liquid pump and means for controlling the operation of said pump, said means comprising a member associated with said pump and adapted to be moved only during the pumping operation, a movable stop, and coin controlled means for moving the stop member into the path of said first mentioned member for limiting the pumping operation, said last named means comprising a pivoted lever operatively connected adjacent one end thereof with said stop member and a reciprocating member adapted to be interlocked with said lever for movement therewith by a coin.

11. In a dispensing apparatus of the character described, in combination, a liquid pump, and means controlled by coins of various denominations for permitting operation of the pump for dispensing correspondingly varying predetermined quantities of liquid, said means comprising lock means for preventing actuation of said pump, a stop member movable into position for limiting the operation of said pump, and means for simultaneously releasing said lock means and moving said stop member into said position, said last named means comprising a lever pivoted mediate the ends thereof having one end operatively associated with said stop member and the other end thereof associated with said locking means operatively connected to said locking means and a movable member adapted to be interlocked with said lever for movement therewith by a coin.

12. In dispensing apparatus of the character described, a liquid pump, a member associated with said pump for movement only upon actuating said pump, means for locking said member against movement to prevent operation of said pump, stop means movable into the path of said member for limiting the movement thereof after dispensing a predetermined quantity of liquid, a lever interconnecting said locking means and said stop means, and coin controlled means for actuating said lever for simultaneously releasing said locking means and moving said stop means into the path of said member.

In testimony whereof we affix our signatures.

SAM I. ESSES.
